UNITED STATES PATENT OFFICE.

CHARLES E. SMITH, OF BROOKLYN, NEW YORK, ASSIGNOR TO REMINGTON TYPE-WRITER COMPANY, OF ILION, NEW YORK, A CORPORATION OF NEW YORK.

TYPEWRITING MACHINE.

Application filed February 21, 1922. Serial No. 538,267.

To all whom it may concern:

Be it known that I, CHARLES E. SMITH, a citizen of the United States, and resident of the borough of Brooklyn, city of New York, in the county of Kings and State of New York, have invented certain new and useful Improvements in Typewriting Machines, of which the following is a specification.

10 My invention relates to typewriting machines and more particularly to means for ensuring that the machine is in proper condition to be received within its inclosing case before the case is closed.

15 To the above and other ends which will hereinafter appear, my invention consists in the features of construction, arrangements of parts, and combinations of devices set forth in the following description and 20 particularly pointed out in the appended claims.

In the drawings, wherein like reference characters indicate corresponding parts in the different views,

25 Figure 1 is a fragmentary vertical fore-and-aft sectional view of a Remington-portable machine embodying my invention, the machine being shown collapsed and partly inclosed within its case.

30 Figure 2 is a like view of the machine shown expanded and the case removed.

Figure 3 is a fragmentary detail plan view, with portions broken away, of the platen shifting mechanism and some of the associated parts.

35 Figure 4 is an enlarged detail fragmentary perspective view of the automatically actuated case shift lock-releasing device and some of the associated parts.

40 Figure 5 is a like view of the same showing also the shift lock key depressed, and the parts locked in shifted position.

In all of the views I have omitted parts of the machine unnecessary to an understanding of my invention in its embodiment 45 therein.

50 My invention relates more particularly to light portable machines and is shown in the present instance embodied in a Remington-portable machine which in many respects is like the machines shown in the following patents: A. W. Smith, 1,342,513,

June 8, 1920; J. B. Holden, 1,386,256, Aug. 2, 1921.

55 In the Remington-portable machine the carriage is supported against movement from its normal or lower case position by the cover of the inclosing case when the latter is closed. This prevents the carriage from shifting backward and forward when the machine is being transported in its case, thus preventing injury to the machine which might result from such shifting of the carriage. If, however, the operator should leave the carriage locked in its shifted position, it would interfere with and prevent the cover from being closed. Any forcible 60 attempt to close the cover at this time might result in injury to the machine or to the cover, or both.

65 By my invention I overcome this difficulty and ensure the proper return of the carriage to normal position before the cover is closed, and thereafter render the case shift locking means ineffective so long as the machine is in condition to be inclosed within its casing. The act of expanding the machine, or rendering it in condition for use, is effective to automatically withdraw the means by which the case shift locking means are rendered ineffective, so that 70 such locking means are again in condition for use.

75 The frame of the machine comprises an outer sheet metal frame 1 and an inner sheet metal frame 2 attached to the frame 1 and by which the various working parts of the machine are supported. A series of segmentally arranged type bars 3 are mounted 80 in guide slots of a type bar segment 4, secured to the inner frame 2 and carrying a pivot wire 5 on which the type bars are mounted. Each type bar has a heel with segmentally arranged gear teeth 6, with which similar teeth 7 on a companion sub-lever 8 are adapted to mesh. The sub-levers 8 are pivoted on a pivot wire 9 carried by a suitably fixed slotted support or segment, not shown. The forward end of each sub-lever 8 is pivoted to a depending link 10 which in turn is pivoted to a second sub-lever 11 fulcrumed at its forward end on a sheet metal combined guide comb and fulcrum plate, designated as a whole by the 85

reference numeral 12. This plate is secured in place at its ends by screws 13 and 14 that are received in tapped openings in ears 15 and 16, respectively, on the side plates of the inner frame 2. Each sub-lever 11 is connected to a depending link 17, which in turn is connected to a key lever 18, pivoted on a pivot wire 19. The rear end of each key lever is guided by and held on its pivot by a guide comb 20 which supports the pivot wire on a fixed part of the machine, whereas the forward end portion of each key lever extends through a guide slot 21 in the forward guide comb 12.

15 The type bars are adapted to be turned on their pivot wire 5 from the inoperative position, shown in Fig. 1, where they remain collapsed relatively to the remainder of the machine on a fixed type rest *a*, to the operative position, or position of use, indicated in Fig. 2. In this last mentioned position the type bars are expanded upwardly from the body of the machine, and each is in a position to be moved rearwardly and downwardly to the printing position, and to strike against the top of a platen 22, when the companion printing key is depressed to actuate its lever 18. The hand actuated means, operable at will and by which the type bars are

20 turned from their inoperative position shown in Fig. 1 to their operative position shown in Fig. 2, comprises a rock shaft 23 mounted at its ends in the side plates of the inner frame 2. One end portion of the shaft has the usual crank arm (not shown) which carries a finger piece operable from the right-hand side of the machine, and which may be locked against movement in either extreme position to which it may be shifted, as usual.

25 The hand controlled rock shaft 23 carries two crank arms 24, one near each side of the machine. The free end of each crank arm is pivoted at 25 to a link 26, which in turn is pivoted at its upper end, as at 27, to a shiftable frame. This frame is designated as a whole by the reference numeral 28, and extends transversely across the machine to points near the sides thereof. The frame 28 is formed with depending guide arms 29 that

30 are mounted to move up and down in companion grooved guides 30, carried by the type bar segment 4. The frame 28 thus mounted for vertical shifting movement from the Fig. 1 to the Fig. 2 position, and vice versa, carries a segmental pad 31 arranged beneath the type bars, and cooperative therewith to control the movements of the type bars around their pivot to either of the two positions shown. Each of the type bars carries a lower case type 32 and an upper case type 33, and in the Remington-portable machine a case shifting movement of the platen may be effected to bring either set of types into use. In Figs. 1 and 2 it will be

35 seen that a sheet metal case shift frame ex-

tends fore-and-aft of the machine and comprises side plates 34. Each of these plates is pivoted at its forward end, as at 35, to a depending link 36, mounted on a pivot pin 37 projecting inwardly from a side plate of the frame 2, and prevented from accidental detachment from its pivot by a cotter pin 38. The rear end portion of each plate 34 is bent to form a horizontally disposed flange 39, to which is secured, by screws 40, a casting 41. This casting is pivoted at 42 to upright crank arms 43, carried by a rock shaft 44, received at its ends in bearing openings in the side plates of the frame 2. The casting carries sheet metal grooved tracks 45 and 46, which receive bearing rollers 47 that also coat with grooved tracks 48 and 49 of a carriage bed 50 which supports the platen 22. The entire carriage, with its platen, is thus supported to travel laterally over the support or casting 41, and to receive a bodily fore-and-aft shifting movement with the case shift frame, of which the support 41 forms a part. Suitable stops (not shown) are employed to limit the case shifting movements of the parts, and springs 51 return the shifted parts to normal, or lower case, position when they are not held in the upper case position against the force of said springs.

In the present construction, the key actuated means for controlling the case shifting movements of the parts, comprises a case shift key lever 52 provided with a key 53 and fulcrumed on the pivot wire 19. This key lever is guided at its forward end portion in a guide slot 54 in the comb plate 12. The lever 52 is connected to an upwardly extending link 55, which in turn is connected, at 56, to a bell crank lever 57. The lever 57 is pivoted on a pin or support 58 which is carried by and projects inwardly from the left-hand side plate frame 2. The depending arm of the bell crank 57 extends in front of a pin 59 which projects inwardly from the left-hand side plate 34 of the shift frame. The depending arm of the bell crank lever 57 thus transmits a rearward movement to the shift frame and the parts carried thereby when the shift key 53 is depressed. A shift lock key 60 is carried by an angular lever 61 which is pivoted at 62 to the lever 52, on the outer side thereof. The lever 61 has a depending arm which terminates in a hook-like engaging or locking member or catch 63, preferably offset slightly to the left of the plane of the main body portion of the lever 61, as best shown in Fig. 5. The pivot 62 which unites the levers 61 and 52 is in the nature of a shouldered screw bolt, secured by a nut 64 to the lever 52 and forming a pivot bearing for the lever 61. A spring 65 is coiled around the shank of the screw bolt and has one free end 66 thereof turned over and bearing against the bottom edge of the lever 61, its other free end 67 bearing against the

upper edge of the lever 52. The force of this spring is thus exerted to return the lever 61 on its pivot 62 to the Fig. 1 position, and to normally maintain it relatively to the lever 52 in the position shown in this figure. A lug 68 formed on and extending laterally from the lower edge of the lever 61 projects under the lever 52, and coacts therewith to limit the return movement of the lever 61 relatively to the lever 52.

A sheet metal locking plate or member 69 is secured in front of the comb plate 12 at the left-hand end thereof, as best shown in Fig. 5. One of the screws 13 secures the upper end of the member 69 in place, whereas a screw 70 connects said member intermediate its ends to the plate 12. The lower end portion of the member 69 slopes forward away from the comb plate and has a slight resiliency, sufficient to permit its lower end to receive a slight adjustment fore-and-aft of the machine, by forcing it rearwardly or allowing it to spring forwardly under control of the left-hand screw 14. Thus this screw is in the nature of a headed screw, the shank of which passes through an opening in the lower end portion of the member 69 and effects a fore-and-aft adjustment of the lower end of the locking member or plate 69. It will be seen that this plate is mounted to the left of the slot 54 in the comb plate 12, and that its lower engaging edge 71 extends below and forward of the lower edge of the comb plate. Pressure applied directly to the shift lock key 60 will first turn the lever 61 on its pivot 62 until the hook-like end 63 of said lever bears against the front face of the plate 69. Since the lever 61 can turn no further at this time, the pressure exerted on the key 60 will carry the key lever 52 down with it until the bill of the hook reaches the edge 71 of the plate. The hook will then be forced beneath said edge, and engaging the latter will prevent a return movement of the lever 61, shift lever 52 and the parts controlled thereby, and will lock the carriage in its case shifted position. In order to release the locking lever 61 and enable the parts to return to normal position, it is merely necessary, with the parts thus far described, to depress the shift key 53. This relieves the engaging pressure exerted by the bill of the hook against the edge 71 of the locking plate. The lever 61 being thus freed from further restraint will be returned by its spring 65 to normal position relatively to the lever 52. This results in withdrawing the bill of the hook from beneath the edge 71 of the locking plate, and when pressure of the operator's finger is released from the depressed shift key 53, the key lever 52 and the parts controlled thereby are returned to normal position by the returning springs 51.

65 The Remington-portable machine is pro-

vided with a carrying case in which the machine may be inclosed before transporting it. The inclosing case includes a baseboard 72, on which the machine is fixedly secured, and a detachable cover 73 having a rear wall 74. Rearwardly projecting fingers 75 are secured to the baseboard and are adapted to enter openings 76 in plates 77 secured to the back wall 74 of the cover. When the machine is collapsed, the carriage properly centered, and in normal or lower case position, the cover may be alined with the baseboard in the rear thereof, with the projections 75 extending into the openings 76. The cover may then be given a pivotal movement on said projections resulting in swinging the cover forward and down around the rear edge of the baseboard to inclose the machine. The rear wall 74 of the cover, as usual, is provided with contacts 78, which in the present instance, are in the nature of rubber blocks secured to and projecting inwardly from the wall 74, near each side wall. These contacts are alined with the end plates 79 of the carriage when the latter is centered on the machine. The purpose of these contacts is to bear against the end plates 79 of the carriage when the cover is closed, and support the weight of the carriage in normal or lower case position, and prevent the carriage from shifting from said position while the machine is being carried in the case, rear end lowermost. This prevents the carriage from shifting back and forth while the machine is being transported in its case, and prevents the resultant injury to the machine that might follow from such shifting movement of the carriage. However, it will be understood, from a consideration of Figs. 1 and 2, that if the operator should leave the case shifting mechanism locked, as indicated in Fig. 2, the carriage would be held in its rearmost shifted position, increasing the lengthwise dimensions of the machine at this point. This would result in the rear ends of the plates 79 of the carriage being maintained in the path of the projections 78 on the cover, and prevent the cover from being closed. The use of any considerable force to close the cover at this time might result in injury to the machine, or to the cover, or to both.

The features thus far described were not invented by me. The purpose of my present invention in the main is to overcome the difficulty pointed out above, and render it impossible to injure the machine or its cover, by providing automatically operating means for releasing the case shift locking means preliminary to inclosing the machine, and thereafter render the case shift lock ineffective until such time as the machine is again in condition for use. It will of course be understood that it is necessary to collapse the machine before it can be inclosed in its

case. In the present instance I utilize the means for collapsing the machine to automatically effect a release of the case shift lock, if it should be held in locked position, and also to thereafter render ineffective such locking means until the machine has been expanded and is again in condition for use. In the particular form of construction herein shown I provide the rock shaft 23, which controls the movement of the type bars into and out of contracted relationship with the remainder of the machine, with an additional crank arm 80. To this crank arm is pivoted, at 81, a two-part adjustable link 82, the parts of which are united by a turn-buckle 83. This enables the parts of the link to be adjusted relatively to each other to lengthen or shorten the link. The forward end of the link 82 is pivoted at 84 to a releasing or controlling member 85, pivoted at 86 on a sheet metal angular bracket 87, secured in place by any suitable means. In the present instance I secure the bracket in place with the aid of the left-hand screw 14 and a nut 88. This member 85 extends through and works in the slot 54 in the comb plate 12, and has a cam face 89 and a contact 90. It will be understood that this member 85 turns on its pivot in a fore-and-aft plane, and in a plane coincident with the plane of the case shift key lever 52. While the member 85 works in the slot 54, and is supported and guided by the side walls thereof, it is nevertheless situated at a point which is low enough to prevent it from interfering with the operation of the key lever 52 which works in the same slot. The plane of the lever 61 is parallel with and to the left of the member 85, and lever 61 carries near the lower end of its depending arm a laterally projecting pin 91 extending therefrom to the right and beneath the key lever 52. The position of the pin 91 is such that when the shift lock key 60 is depressed and maintained locked, as indicated in Fig. 2, said pin will be in front of the cam 89, and adapted to be acted on thereby when the cam carrying member is moved from the Fig. 2 to the Fig. 1 position. The effect of this movement of the cam face 89 is to effect a downward and forward camming action on the pin 91, thereby turning the lever 61 on its pivot 62 until the bill of the hook is freed from the edge 71 of the locking plate. The spring 65 is then immediately effective to restore the lever 61 to the position it normally bears to the lever 52, and the latter being freed from further restraint will, together with the parts controlled thereby, return to normal position. The effect of this is that the carriage will move forward from the Fig. 2 position to that indicated in Fig. 1, and said carriage will no longer offer an obstruction to the closing of the cover to insure close the machine.

When the hand controlled rock shaft 23, and the parts controlled thereby, are moved from the Fig. 2 to the Fig. 1 position, and result in automatically releasing the case shifting locking means as stated, the member 85 will be retained in the position shown in Fig. 1 until the shaft 23 and the parts controlled thereby are again moved to restore the machine to the condition of use, shown in Fig. 2. The member 85 being thus retained in the Fig. 1 position presents the contact face or edge 90 thereof in a position where it will be in the path of and coat with the pin 91, to prevent an engagement of the locking hook of the lever 61 with the edge 71 of the locking plate. It follows therefore that if, after the case shift lock is automatically released in the manner stated, the operator should again depress the shift lock key 60, it will be ineffective to lock the case shift mechanism, and it does not again become effective until the member 85 is automatically withdrawn by actuating the shaft 23 to place the machine in condition for use, as shown in Fig. 2. It will be observed that even if the case shift mechanism be not locked in the upper case position prior to collapsing the machine, there is nothing to prevent the operator from actuating the case shift mechanism after the machine has been collapsed, but before inclosing it in its case. If the case shift mechanism could be locked in its shifted position at this time, and in the manner indicated, it would prevent the cover from being closed, notwithstanding the machine is collapsed. However, since the member 85 is maintained in the effective position so long as the machine remains collapsed, this renders the locking means ineffective. If therefore the operator at this time should depress the shift lock key 60, the lock would not engage, and when pressure of the operator's finger is released from said key the shifted parts will return to normal position, and the cover may be closed without any injurious result.

The adjustment of the link 82 enables me to regulate the point of release in the operation of the member 85, and to compensate for any adjustment of the lower end of the plate 69 that may be effected.

In the Remington-portable machine several specifically different forms of case shifting means and case shift locking means have been employed, the means shown representing one form of such mechanism. It should be understood however that the devices of my invention, with possible slight modification in the construction and arrangement of the parts, may be applied to the different forms referred to.

As hereinbefore indicated I have shown only so much of the Remington-portable machine, as at present constructed, as may be necessary to arrive at an understanding

of my invention in its embodiment therein. The invention may be readily embodied in that machine without modifying or materially modifying the structural features thereof as they now exist, the change in the main being the addition of the parts 85, 87, 82, 80 and 91. Nevertheless, I desire to have it understood that the invention is not restricted to its embodiment in a machine 10 of the character shown. So far as I am aware I am the first to provide in combination with a part of a typewriting machine, which in its ordinary operation may be shifted to and locked in an abnormal position 15 where it prevents the case of the machine from being closed, automatically operating means for ensuring the restoration of said part to normal position before the case is closed, and wish to be understood as claiming such combination broadly, 20 as well as the more specific features set forth in some of the accompanying claims.

Various changes may be made without departing from my invention as the same is 25 defined in the accompanying claims, and certain features thereof may be employed without others.

What I claim as new and desire to secure by Letters Patent, is:—

30 1. In a typewriting or like machine, the combination of a platen, printing instrumentalities, means for effecting a relative case shifting movement between the two, means for locking the shiftable part in its shifted position, means operable at will for releasing said locking means, and automatically operating means for releasing said locking means preliminary to inclosing the machine within its case.

40 2. In a typewriting or like machine, the combination of a platen, printing instrumentalities, means for effecting a relative case shifting movement between the two, means for locking the shiftable part in its shifted position, means for collapsing a portion of said machine, and means controlled by said collapsing means for releasing said locking means.

45 3. In a typewriting or like machine, the combination of a platen, printing instrumentalities, means for effecting a relative case shifting movement between the two, means for locking the shiftable part in its shifted position, means operable at will for releasing said locking means, and automatically operating means for maintaining indefinitely said locking means inoperative.

60 4. In a typewriting or like machine, the combination of a platen, printing instrumentalities, means for effecting a relative case shifting movement between the two, means for locking the shiftable part in its shifted position, means for collapsing a portion of said machine, and means controlled

by said collapsing means for releasing said locking means and rendering it ineffective so long as said portion of the machine remains collapsed.

5. The combination of a platen of a typewriting or like machine, printing instrumentalities, means for effecting a relative case shifting movement between the two, means for locking the shiftable part in its shifted position, means for collapsing a portion of said machine, a casing in which the machine may be inclosed and which is prevented from being closed when said locking means retains said shiftable part in the abnormal or shifted position, and means controlled by said collapsing means for releasing said locking means and allowing the shiftable part to return to normal position in order that the casing may be closed and inclose the machine.

6. In a typewriting or like machine, the combination of a platen, means for effecting a substantially horizontal case shifting movement of the platen thereby increasing the fore-and-aft dimensions of the machine at this point, case shift locking means for retaining the platen in its shifted position, means operable at will for releasing said locking means, and automatically operating means for releasing said locking means and permitting the platen to return to normal position.

7. In a typewriting or like machine, the combination of a platen, means for effecting a case shifting movement of the platen thereby increasing the dimensions of the machine at this point, case shift locking means for retaining the platen in its shifted position, a part that is movable into and out of contracted relationship with the machine, and means controlled by the movement of said part into contracted relationship for releasing said locking means.

8. In a typewriting or like machine, the combination of a platen, means for effecting a case shifting movement of the platen thereby increasing the dimensions of the machine at this point, case shift locking means for retaining the platen in its shifted position, a part that is movable into and out of contracted relationship with the machine, and means controlled by the movement of said part into contracted relationship for releasing said locking means and for thereafter rendering said locking means ineffective so long as said part remains in its contracted position.

9. In a typewriting or like machine, the combination of a platen, means for effecting a case shifting movement of the platen, case shift locking means for retaining the platen in its shifted position, a series of type bars movable into and out of contracted relationship with the remainder of the machine,

means for thus moving said type bars, and means controlled by said moving means for automatically releasing said locking means.

10. In a typewriting or like machine, the combination of a platen, printing instrumentalities, means for effecting a relative case shifting movement between the two, means including a key actuated catch movable by its key into locking position for locking said shiftable part in its shifted position, means operable at will for releasing said catch, and means independent of a printing operation of the machine and of said first mentioned releasing means for 15 automatically moving said catch to its releasing position.

11. In a typewriting or like machine, the combination of a platen, printing instrumentalities, means for effecting a relative 20 case shifting movement between the two, means including a key actuated catch movable by its key into locking position for locking said shiftable part in its shifted position, means operable at will for releasing said catch, and means independent of a printing operation of the machine and of 25 said first mentioned releasing means for automatically moving said catch to its releasing position and for thereafter preventing said catch from being effective until the automatically operated moving means are restored to normal position.

12. In a typewriting or like machine, the combination of a carriage that in its 35 entirety receives a bodily case shifting movement fore-and-aft of the machine, locking means for retaining the carriage in its shifted position, means operable at will for releasing said locking means, and automatically operating means for releasing said locking means and allowing it to return to normal position.

13. In a typewriting or like machine, the combination of a series of key controlled 45 type bars, controlling means for simultaneously moving said type bars from their normal position of use into a more compact relation with reference to the remainder of the machine and where they are ineffective 50 for operation by their keys, a platen, means for effecting a case shift movement of said platen, locking means for holding the platen in its case shifted position, and means controlled by said controlling means for releasing said locking means when the controlling means are actuated to move the type bars into compact relation.

14. In a typewriting or like machine, the combination of a series of key actuated type 60 bars, controlling means for simultaneously moving said type bars from their normal position of use into a more compact relation with reference to the remainder of the machine, a platen, means for effecting a

case shift movement of said platen, locking 65 means for holding the platen in its case shifted position, and means controlled by said controlling means for releasing said locking means when the controlling means are actuated to move the type bars into compact relation and for thereafter rendering said locking means ineffective until the controlling means are again actuated to return the type bars to the normal position of use. 70

15. In a collapsible typewriting or like machine, the combination of means including a rock shaft operable at will for controlling the collapsing movement of parts of the machine, type bars, a platen, means for effecting a relative case shifting movement between the platen and type bars, locking means for locking the shifted part in case shifted position, and means controlled by said rock shaft for releasing said locking means when the shaft is rocked to collapse the machine. 85

16. In a collapsible typewriting or like machine, the combination of means including a rock shaft operable at will for controlling the collapsing movement of parts of the machine, type bars, a platen, means for effecting a relative case shifting movement between the platen and type bars, locking means for locking the shifted part in case shifted position, and means controlled by said rock shaft for releasing said locking means when the shaft is rocked to collapse the machine and for preventing the locking means from being effective so long as the machine remains collapsed. 95

17. The combination of a platen, printing instrumentalities, means for effecting a relative case shifting movement between the two, and automatically operating means for ensuring that the case shifting member is in normal position before the machine can be inclosed in its case. 100

18. The combination of a platen, printing instrumentalities, means for effecting a relative case shifting movement between the two, an inclosing case for the machine having a part that holds the shiftable member against case shifting movement from normal position when the casing is closed, and automatically operating means for ensuring that the case shifting member is in normal position before the machine can be inclosed in its case. 115

19. The combination of a carriage mounted for case shifting movement, an inclosing casing having a cover with a contact thereon that coacts with the carriage to support it in normal position against case shifting movement, and automatically actuated means for ensuring that the carriage is in normal case position before the cover can be closed on the machine. 120

20. In a typewriting or like machine, the

combination of a part thereof which in the ordinary operation of the machine may be shifted to and locked in an abnormal position and which when in said abnormal position prevents the case for the machine from being closed, and automatically operating means for ensuring the restoration of said part to normal position before the case is closed.

10 21. The combination of case shifting mechanism for a typewriting or like machine, means for locking said case shifting means to hold the shiftable part in case shifted position, a casing for inclosing said machine, a

part of the machine which it is necessary to 15 actuate when the machine is in condition for use before it can be inclosed in said casing, and means controlled by said part for automatically releasing said locking means.

Signed at the borough of Manhattan in 20 the city of New York, in the county of New York and State of New York this 20th day of February, A. D. 1922.

CHARLES E. SMITH.
